UNITED STATES PATENT OFFICE.

ADOLPH BAUER, OF NEWARK, NEW JERSEY, ASSIGNOR TO RICHARD C. JENKINSON,
DOING BUSINESS AS R. C. JENKINSON & CO., OF NEWARK, NEW JERSEY.

AIR PURIFIER OR HUMIDIFIER AND INHALER.

Application filed March 20, 1924. Serial No. 700,496.

To all whom it may concern:

Be it known that I, ADOLPH BAUER, a citizen of the Republic of Germany, and a resident of Newark, in the county of Essex and State of New Jersey, have invented new and useful Improvements in Air Purifiers or Humidifiers and Inhalers, of which the following is a specification.

This invention relates in general to air purifiers or humidifiers and inhalers of the type in which a purifying, perfuming or humidifying substance or a medicament is vaporized by contact with a circulating fluid such as air or steam. The invention is particularly intended for use in sick rooms for purifying or perfuming the air, or for medicating the air or for use as an inhaler for relief of asthma, colds, etc.

The primary object of the invention is to provide a device of the character described embodying novel and improved features of construction so as to be adapted to cooperate with either the vent valve of a steam heated radiator to utilize the steam therefrom for vaporizing the purifying, medicating, etc. substance or with a special boiler for generating steam for vaporizing said substance, accordingly as steam is available in the radiator or as the user may desire.

Another object is to provide a device of the general character described comprising a casing to receive a purifying or medicating, etc. substance and constructed to permit flow of a fluid therethrough into contact with said substance to vaporize the latter, said casing being adapted to be connected to a radiator vent valve to receive steam therefrom, and means carried by said casing to regulate the opening and closing of said valve to vary the flow of steam.

A further object is to provide such a device comprising a casing having a steam chamber provided with an opening in the top thereof, and a vaporizer casing to receive a purifying or medicating, etc. substance adapted to removably fit into said opening and formed with a passage to permit steam to flow from said chamber through said casing into contact with said substance to vaporize the same and discharge the vapor into the atmosphere.

Other objects are to provide a combination with a radiator vent valve, of a steam chamber casing secured to the casing of said vent

valve exteriorly thereof to receive steam from the outlet of said valve, said steam chamber casing having an outlet opening, and a vaporizer casing adapted to fit into said opening and to receive a purifying, etc. substance, said vaporizer casing having a passage to permit steam to flow from said chamber into contact with said substance to vaporize the same; to provide such a combination in which the vaporizer casing is provided with means to regulate the opening and closing of said vent valve; to provide a novel and improved vaporizer casing, and to obtain other results and advantages as may be brought out by the following description.

Referring to the accompanying drawings, in which the same reference characters designate corresponding and like parts.

Figure 1 is a vertical longitudinal sectional view through a device constructed in accordance with my invention including a vaporizer, a steam chamber for generating steam for the vaporizer and a heating device for generating steam in the steam chamber;

Figure 2 is a top plan view of the device shown in Figure 1;

Figure 3 is a bottom plan view of the vaporizer taken on the line 3—3 of Fig. 1;

Figure 4 is a vertical longitudinal sectional view through another form of the invention in which the vaporizer casing shown in Figure 1 is used on a steam radiator vent valve.

Figure 5 is a view similar to Figure 4 showing a modified form of vaporizer and connection thereof to a radiator vent valve;

Figure 6 is a horizontal sectional view taken on the line 6—6 of Figure 5, and

Figure 7 is a horizontal sectional view taken on the line 7—7 of Figure 5.

In the specific embodiment of the invention shown in Figures 1 to 4 of the drawings, the reference character 1 designates a vaporizer casing having one end thereof threaded as at 2 and formed with a transverse partition or diaphragm 3 between the ends thereof, both ends of said casing being open. A plug 4 is arranged coaxially in the diaphragm 3 and is provided with a plurality of passages 5 communicating between the ends of the casing at opposite sides of the diaphragm 3. The end of said plug projecting through the diaphragm 3 at the

threaded end 2 of the casing is provided with an extension 6 for a purpose hereinafter described. The other end of the plug is provided with a recess 7 forming a bearing for an agitating and mixing fan 8 which may be of any suitable construction. In the present instance said fan comprises a hub 9 having an axial stub shaft 10 therethrough one end of which is adapted to fit within 10 the opening 7 of the plug 4 while the other end projects from the opposite side of the fan. Two discs 11 and 12 of suitable absorbent material, such as asbestos, are arranged within the casing 1, preferably one at each 15 side of the diaphragm 3, said discs being adapted to be saturated with a suitable purifying, medicating, etc. substance.

The vaporizer above described is intended to be used with a plurality of types of steam 20 chambers for supplying steam for vaporizing the purifying, medicating, etc. substance. In Figure 1 of the drawings the vaporizer is shown as used in connection with a steam boiler 13 having a steam chamber 14 in one 25 end thereof, the top wall of which is provided with a threaded opening 15 to receive the threaded end 2 of the casing 1. The other end of the steam boiler 13 is adapted to be set upon a suitable heater casing 16 30 to receive a heater of any known type such as the alcohol burner 17. The boiler 13 is adapted to contain water from which is generated steam by the heater 17 for vaporizing the purifying, etc. substance in the 35 vaporizer 1.

In the operation of this form of the invention, the steam generated in the steam chamber 14 passes upwardly into the casing 1 and into contact with the disc 12, thence 40 through the passages 5 of the plug 4 into the other end of the casing and into contact with the disc 11. The purifying, etc. substance carried by said discs is thus vaporized by the steam and passes outwardly 45 through the upper end of the casing 1. The mixing fan 8 being arranged above the passages 5 is driven by the jets of vapor therefrom so as to thoroughly agitate the vapors and distribute them into the 50 atmosphere above the vaporizer. If desired, to increase the strength of the vapors, an absorbent disc 18 may be arranged on the upper side of the fan 8 and held in position thereon by the end 10 of the shaft of the fan 55 projecting through an opening 19 in the disc. It will be observed that this device is simple and inexpensive in construction and operation, can be easily carried from room to room as may be desired, and occupies a minimum amount of space. Where it is desired 60 to use the device as an inhaler, an inhaler tube 180 may be applied to the upper end of the casing 1 so as to direct the vapors for the purpose of inhalation.

65 Preferably the steam boiler 13 is designed

to be heated by different sources of heat so as to be adapted for use under various conditions. Thus, the boiler may be formed with a recess 130 to receive an electric heater where electricity is available, this being a 70 much handier and simpler means of generating steam than the heater 17. It will also be understood that the boiler 13 may be set upon a conventional stove or oil heater if such is preferable to the electric or alcohol heater above described. 75

In Figure 4 I have shown the vaporizer used in connection with the vent valve of a steam radiator. The vent valve may be generally of known construction including 80 a casing 20 having a valve chamber therein and adapted to be connected to a radiator in the usual manner by means of the threaded nipple 21 which communicates with the valve chamber. The said chamber is formed with 85 an outlet opening 22 controlled by a needle valve 23 actuated by any known mechanism to control the outlet 22. The valve casing is exteriorly threaded at 25 to receive a correspondingly threaded end 26 of a fluid 90 chamber casing 27 the other end of which is interiorly threaded at 28 to receive the threaded end 2 of the casing 1. With this construction the air escaping from the radiator as the steam rises therein may be utilized 95 for vaporizing the purifying, etc. substance, and after the vent valve 23 has automatically closed the outlet 22 the steam from the radiator may be utilized by rotating the casing 1 in the casing 27 to bring the projection 6 of the plug 4 into engagement with the valve 23 to hold the same in open position. The extent of the opening of the said valve 23 may be easily regulated by rotation of the casing 1 in the proper direction. 100 The steam flows from the vent valve into the chamber 27 and from there into the casing 1 to vaporize the substance in the discs 11 and 12, exactly as above described.

105 The casing 27 may also be utilized as a 110 vaporizer. For this purpose a passage 29 in the vent valve casing 20 may be provided to permit steam to flow from the vent valve directly into the steam chamber between the casing 27 and the casing of the vent valve, 115 and a plurality of spacedly superposed rings 30 of absorbent material may be arranged in said chamber to receive a purifying, etc. substance which will be vaporized by contact of the steam with the said rings. 120

125 It will thus be seen that the vaporizer 1 may be utilized with a steam radiator when steam is available therein, or may be used in connection with a special steam generator, such as the boiler 13, when steam is not available in the radiator, or portability of the device is necessary.

A modified form of vaporizer casing is shown in Figures 5 to 7 inclusive and includes a casing or fluid chamber 31 having 130

a threaded opening 32 in one end thereof to be secured to a threaded projection 33 on the outlet end of a radiator vent valve 34. The said valve may be otherwise identical in construction with the valve 20, the outlet thereof being controlled by a needle valve 35. A vaporizer casing 36 has one end thereof threaded into the end of the casing 31 opposite the opening 32, said end of the vaporizer casing being closed except for a plurality of transverse openings 37. A plug 38 is secured axially in said end of the vaporizer casing and is provided at the end thereof projecting into the casing 31 with an extension 39 to engage the end of the vent valve 35. The end of the plug 38 within the vaporizer casing 36 is formed with an opening 40 to serve as a bearing for the shaft 41 of a mixing fan 42 which may be identical in construction with the fan 8 shown in Figure 1. An absorbent disc 43 of any suitable material, such as asbestos, is secured to the end of the vaporizer casing projecting into the main casing 31 and is formed with a plurality of transverse openings 44 corresponding in number to the openings 37 in the vaporizer casing. Another absorbent disc 45 may be arranged in the casing adjacent the opening 32. The outer end of the vaporizer casing is preferably closed by a removable cover 46 having its top perforated or formed of wire screen 47, and an absorbent disc 48 is preferably arranged within said cover.

When the vent valve 35 is open and air is escaping therefrom, said air may be utilized for vaporizing the substance in the absorbing discs 43, 45 and 48. When it is desired to utilize steam from the radiator, the auxiliary casing 36 is rotated to move the extension 39 of the plug 38 into engagement with the valve 35 to hold the same in open position and permit the escape of steam from the vent valve into the main casing 31. The air or steam in the main casing 31 contacts with the discs 43 and 45 and passes therefrom through the openings 37 into the auxiliary casing and from there through the disc 48 and wire screen 47 into the atmosphere. The jets of air or steam from the openings 37 actuate the mixing fan 42 in a manner similar to that in which the jets from the passages 5 actuate the fan 8 in the construction shown in Figure 1.

It will be noted that each of the forms of the invention includes a fluid chamber connected to a source of vaporizing fluid, and a vaporizer casing connected to the fluid chamber whereby fluid may flow from the fluid chamber through the vaporizer casing into contact with the substance to be vaporized in the vaporizer casing.

It will be understood that the number, construction and arrangement of the absorbent discs may be varied, and that any suit-

able material for receiving the purifying, medicating, etc. substance may be utilized. Furthermore, while I have shown the vaporizer casings as embodying certain details of construction, it will be understood that this is only for the purpose of illustrating the principles of the invention and that many modifications and changes may be made in the details thereof without departing from the spirit or scope of the invention. Therefore, I do not desire to be understood as limiting myself except as required by the following claims when construed in the light of the prior art.

Having thus described the invention, what I claim is:

1. A vaporizer comprising a main casing to be connected to a valved source of vaporizing fluid and having an outlet, and a vaporizer casing containing a substance to be vaporized having an inlet to connect to said outlet of said main casing and an outlet whereby fluid may flow from said source through the main casing and the vaporizer casing to vaporize said substance, said vaporizer casing being adjustable upon said main casing to engage the valve of said source of vaporizing fluid to regulate the flow of fluid therefrom through said vaporizer casing.

2. A vaporizer comprising a main casing to be connected to a valved source of vaporizing fluid and having a screw threaded outlet, and a vaporizer casing containing a substance to be vaporized having one end screw threaded to adjustably fit into said screw threaded outlet of the main casing and formed with an inlet to receive fluid from said main casing, said vaporizer casing having a part to engage the valve of said source of fluid to regulate said valve upon screwing of the vaporizer casing into and out of said main casing, said vaporizer casing being also formed with an outlet whereby fluid may flow from said main casing through said vaporizer casing to vaporize said substance.

3. The combination with a radiator vent valve including a housing having an outlet opening and a vent valve for controlling said opening, of a vaporizer casing connected to said outlet opening of said housing of the vent valve and containing a substance to be vaporized and permitting the flow of fluid from said vent valve into contact with said substance, and means on said vaporizer casing for regulating the opening and closing of said vent valve.

4. The combination with a radiator vent valve including a housing having an outlet opening and a vent valve for controlling said opening, of a fluid chamber mounted on said housing of said vent valve over said outlet opening to receive fluid therefrom, a vaporizer casing connected to said fluid

- chamber and containing a substance to be vaporized and permitting flow of fluid from said chamber into contact with said substance to vaporize the same, and means on said vaporizer casing for regulating the opening and closing of said vent valve.
5. The combination with a radiator vent valve including a housing having an outlet opening and a vent valve for controlling said opening, of a fluid chamber mounted on said housing of said vent valve over said outlet opening to receive fluid therefrom, and a vaporizer casing having a screw threaded connection with said fluid chamber and containing a substance to be vaporized said casing permitting flow of fluid from said chamber into contact with said substance to vaporize the same and constructed to regulate opening and closing of
- 20 said valve by rotation of said casing on said chamber.
6. The combination with a radiator vent valve including a housing having an outlet opening and a vent valve for controlling said opening and having one end projecting from said opening, of a fluid chamber mounted on said vent valve housing over said outlet opening, and a vaporizer casing having a screw threaded connection with said fluid chamber and containing a substance to be 25 vaporized, said vaporizer casing permitting flow of fluid therethrough from said chamber into contact with said substance and being constructed to engage said projecting end of the vent valve and regulate opening and closing thereof by rotation of said casing on said fluid chamber.

ADOLPH BAUER.
